[57] **ABSTRACT**

A control device selectively applies friction to a control mechanism adapted for feeding lathe knives in a grinding machine, whereby overrun of the mechanism or inaccuracy in its operation is substantially prevented. The control device is selectively locked out of its friction-applying position to allow rapid insertion and removal of knives.

FRICITION CONTROL DEVICE

BACKGROUND OF THE INVENTION

The present invention relates to a friction control device for a machine tool feeding mechanism and particularly to a friction control device applicable for maintaining accuracy of feed.

In a type of grinding machine commonly employed for grinding large lathe knives used in plywood veneer peeling lathes, a feeding mechanism moves a knife being ground progressively closer to a grinding wheel after each pass of the grinding wheel along the knife. The feed is, of course, accurately predetermined whereby the desired amount of metal is ground away on each pass, the automatic feed mechanism generally comprising a ratchet device for moving the knife blade closer to the grinding wheel by a predetermined amount for each operation of the ratchet device. Unfortunately, machine operation and inertia of components is such that the feed mechanism tends to overshoot. Thus a ratchet pawl is apt to urge a feed wheel farther than just the amount of pawl movement. It is, of course, possible to provide excessive friction in the operation of the feed mechanism by maintaining tight feed screw tolerances and/or applying axial pressure to the feed screw such that no overrun or the like will ordinarily take place. However, application of friction in this way hampers the manual operation of the feed device for inserting or replacing knives to be ground. Thus, a feed wheel associated with the feed mechanism may typically have to be rotated by as many as 65 to 70 revolutions for moving the machine bed plate to a position where a new blade can be inserted. Therefore, friction control is not apt to be employed inasmuch as the machine output is correspondingly reduced when additional time is required in changing knives. In the usual case, the machine operator closely monitors the feed in order that inaccuracy or overrun of the feed can be corrected after each pass of the grinding mechanism, and then the operator changes blades.

SUMMARY OF THE INVENTION

According to the present invention, an improved friction control device comprises a bracket frame adapted to be secured to the main frame of a grinding machine or the like, this bracket frame slidably supporting a shaft carrying an arcuate shoe positioned adjacent the periphery of a feed wheel or control wheel. The shoe is provided with a frictional surface for normally contacting the periphery of the feed wheel and preventing overrun of the automatic feed mechanism. The friction control device is further provided with a means for rapidly upraising and locking the aforementioned shoe out of contact with the feed wheel whereby the machine operator can rapidly and conveniently remove the frictional force and rapidly transfer the machine bed plate into and out of position, as when changing knives. The mechanism thus provides for accurate and versatile machine operation. Moreover, the friction control device is economical in construction and easily mounted upon the machine without requiring extensive alteration or even disassembly of the machine.

It is accordingly an object of the present invention to provide an improved friction control device for accurately controlling the feed of a machine tool.

It is another object of the present invention to provide an improved friction control device for a machine

tool, which device is adaptable for normally enhancing the accuracy of feed operation of the machine tool, while being readily controllable to facilitate alternative rapid feed operation.

It is another object of the present invention to provide an improved friction control device for a machine tool, which device is economical in operation and readily and easily attached to such tool without requiring remanufacture or even disassembly thereof.

It is a further object of the present invention to provide an improved friction control device for a ratchet control feed mechanism, which device is adapted for preventing overrun of such mechanism as well as backlash in cooperating parts.

The subject matter which we regard as our invention is particularly pointed out and distinctly claimed in the concluding portion of this specification. The invention, however, both as to organization and method of operation, together with further advantages and objects thereof, may best be understood by reference to the following description taken in connection with the accompanying drawings wherein like reference characters refer to like elements.

DRAWINGS

FIG. 1 is a plan view of a machine for grinding chipper and lathe knives or the like, such machine including a new and improved friction control device;

FIG. 2 is an enlarged vertical cross section, partially broken away, taken through the automatic feed mechanism of the FIG. 1 machine at line 2-2 in FIG. 1, more clearly illustrating the aforementioned friction control device;

FIG. 3 is an end view of the automatic feed mechanism of the FIG. 1 machine having the said friction control device mounted thereon; and

FIG. 4 is a cross-sectional view taken at 4-4 in FIG. 2 through the tension adjustment portion of the aforementioned friction control device.

DETAILED DESCRIPTION

The present invention is effective in combination with a grinding machine of the type employed for grinding veneer peeling lathe knives, for improving the operation of such machine. The general structure of the grinding machine is known, an example being of the type manufactured by Capitol Machine Company, Inc., Indianapolis, Indiana.

The grinding machine 10 includes automatic work feeding mechanism 12 slidably mounted upon a guideway 16 of a main frame 14, such feeding mechanism specifically including a slide 22 movable along the guideway and having a threaded connection with a feed screw 17. The right-hand end of the grinding machine is provided with a similar mechanism (not shown) operated via bevel gears 89 and shaft 114. Inward feed of the knife to be sharpened is accomplished by rotation of feed wheel 62, either automatically or by means of hand wheel 71 connected thereto, which turns the feed screw 17. A bed plate 20 connects slides 22, at each end of the machine, and such bed plate supports knife clamps 24 for securing a knife 26 to the top surface 28 of the bed plate in the proper position to be ground by a grinding wheel 30 carried on the end of shaft 32 of motor 34. The motor 34 is secured to a carriage 36 which moves longitudinally along supports 38, forming part of the main frame 14 of the grinding machine. The

carriage 36 is fed leftwardly and rightwardly by means of a feed screw 40 rotated with a reversible motor 42 via belt drive 44. The grinding wheel 30 moves back and forth across the face of the knife 26 sharpening the same at the desired angle.

On the completion of each cycle of longitudinal movement, the carriage 36 contacts an upstanding rod 46 of an advancing means 48, moving the rod to the left in FIG. 1 for rotating connecting rod 50. Affixed to one end of rod 50 is a vertical bar 52 from which a pawl 54 is pivoted at 56. End 58 of the pawl 54 engages ratchet teeth 60 formed on an outer periphery of feed wheel 62 for rotating feed screw 17 and advancing bed plate 20 on guideways 16 a predetermined distance toward grinding wheel 30. Therefore, upon the next longitudinal movement of carriage 36, the grinding wheel 30 will grind off a few more thousandths of an inch of material from the knife.

According to the present invention, friction control device 70 causes the feed mechanism to maintain an even, calibrated grinding feed. This device includes an angularly bent bracket frame 72 comprising a steel bar having its lower vertical portion attached by bolts 74 to the main frame 14 of the grinding machine, and specifically by way of a brace 73. The upper angular portion 82 of the bracket frame is provided with a depending flat apron or shield 76 disposed at right angles to the bar. This apron keeps arcuately shaped shoe 84 of the friction control device in general alignment with smooth peripheral surface 88 of feed wheel 62 which is located adjacent the aforementioned teeth 60. Thus, the shoe 84 is prevented from being turned crossways of the control wheel or interfering with the operation of the tooth and ratchet mechanism. The apron also aids in preventing injury to the operator by acting as a forward safety guard in front of the ratchet and friction mechanisms. The forward edge of the apron is adjacent the shoe, and is also suitably arcuate in contour.

A shaft 78 extends through a bushing 80 welded into an aperture in the upper portion 82 of the bracket frame 72 (see FIGS. 2 and 4), and welded to the lower end of the shaft 78 is the aforementioned arcuately shaped shoe 84, having a lining 86 suitably in the form of rubber-faced cotton fabric belting secured thereto with contact cement. A face of this lining 86 normally contacts smooth cylindrical surface 88 of feed wheel 62 (to the right of teeth 60 in FIG. 3). It will be seen that shaft 78 and apron 76 are substantially parallel. Elements 86 and 88 have the same radius.

The upper end of the shaft 78 is threaded at 90 to receive jam nut 92, and a cap nut 94. A locking collet 96 is movable on the shaft between bushing 80 and jam nut 92, collet 96 being provided with an upper knurled radial flange 104. As can be seen in FIG. 2, the locking collet 96 has a pair of V-shaped male dovetail portions or detent cams 98 on its lower edge, normally received within matching V-shaped female dovetail portions 100 along the top edge of bushing 80. The dovetail portions are spaced by approximately 180° around shaft 78. A spring 102 is positioned on shaft 78 between the top of the shoe 84 and the bottom of the bushing 80 and with the collet 96 in the position illustrated a constant pressure can be maintained between the lining 86 and smooth cylindrical surface 88 of wheel 62. When it is desired to release this pressure, the knurled flange 104 of the collet 36 is manually upraised and rotated by 90° for raising the male dovetail or detent cam 98 up out

of the matching female dovetail 100 and onto cylindrical edge portion 106. The shoe 84 is raised thereby above the cylindrical periphery of wheel 62 and is effectively locked in this position whereby wheel 62 may turn freely.

With the shoe 84 in its lower friction-applying position, the automatic feeding mechanism, including such mechanism at each end of the grinding machine, is constrained to provide a smooth and accurate feed after each pass of the grinding wheel 30. The pawl 54 advances the feed wheel 62 the desired amount, corresponding to the pawl movement, without overrun of the control wheel, that is without free wheeling of the control wheel to a further angular position. Moreover, backlash in the mechanism including the feed screw 17 and slide 22 as well as bevel gears 99 and subsequent mechanism is substantially eliminated. Therefore, an accurate and uniform preset feed can be maintained for the ratchet mechanism.

However, when extensive rotation of feed wheel 62 is desired as in the case of outward movement of bed plate 20 for removing a knife and inward movement of the bed plate for carrying a knife to the sharpening position, the friction control device 70 is upraised by upraising the knurled flange 104 and rotating the same by approximately 90°. The shoe 84 now releases the feed wheel 62 to a free wheeling condition whereby a machine operator can rapidly rotate the feed wheel (by means of hand wheel 71) and move the bed plate in and out. Thus, accurate automatic feed of the grinding machine is maintained by the present invention as desired, but the friction control device is readily and easily released as required for rapid operation of the mechanism.

Consequently, the friction control device according to the present invention allows maximum utilization of operator time. The operator need not constantly watch the automatic feed mechanism in order to insure the correct feed is accomplished after each pass of the grinding wheel. Therefore, the operator is freed for other duties when a knife is being ground. Furthermore, when a knife is ground and it is desired to remove the same and place a second knife in the machine for grinding, the operator can rapidly move the knife-carrying bed plate in and out without having to urge the feed mechanism slowly against a permanent anti-backlash or friction device.

While we have shown and described the preferred embodiment of our invention, it will be apparent to those skilled in the art that many changes and modifications may be made without departing from our invention in its broader aspects. We therefore intend the appended claims to cover all such changes and modifications as fall within the true spirit and scope of our invention.

We claim:

1. In a feed mechanism for a machine tool having a rotatable feed wheel for bringing about relative motion between the work and machining means, a friction control device comprising:
bracket frame means adapted to be secured to the frame of said machine tool;
an arcuate shoe positioned by said bracket frame means proximate the periphery of said feed wheel, said shoe having a lining material for contacting the periphery of said feed wheel in frictional relation;

means for urging said shoe toward said feed wheel to produce frictional engagement therewith; and means for selectively securing said shoe in upraised position relative to said feed wheel for freeing said feed wheel from frictional engagement.

2. The device according to claim 1 wherein said means for selectively securing said shoe comprises cooperative cam members, and means for operating one of said cam members for selectively upraising said shoe relative to said feed wheel.

3. The device according to claim 2 including a shaft secured to said shoe, said shaft being slidably supported by said bracket frame means for movement toward and away from said feed wheel, said cam members comprising cylindrical cam members disposed substantially coaxially with respect to said shaft, one of said cam members being secured to said bracket frame means and the other being rotatable for moving said shaft and the shoe carried thereby in a direction longitudinal of said shaft.

4. In a grinding machine including a main frame and grinding means, and having a rotatable feed wheel adapted to bring about relative motion between work and the said grinding means in response to cyclical grinding operation, wherein relative movement also occurs between said grinding means and the work in a direction therealong, a friction control device comprising:

a bracket frame adapted to be secured to the main frame of said grinding machine, said bracket frame having an aperture;
 a shaft extending through said aperture in said bracket frame and slidably with respect thereto, said shaft carrying an arcuate shoe positioned by said bracket frame proximate the periphery of said feedwheel, said shoe carrying lining material for contacting the periphery of said feedwheel in frictional relation;
 a spring carried by said shaft between said bracket frame and said shoe for biasing said shoe toward said feedwheel to exert force between said lining and said feedwheel;
 and means carried by said shaft on the reverse side of said bracket frame from said spring for selectively locking said shoe in an upraised position relative to said feedwheel and freeing said feedwheel from frictional engagement.

5. The device according to claim 4 wherein said

means for selectively locking said shoe in an upraised position comprises cooperating cylindrical cam members respectively attached to said bracket frame and rotatable on said shaft while being longitudinally engageable therewith, said cam members having a first cooperating position providing the closest axial spacing thereof along said shaft adapting said shaft to carry the arcuate shoe lining material into frictional contact with the said feedwheel, and an upraised level position for 10 locating the arcuate shoe lining material out of contact with the periphery of said feedwheel.

6. The device according to claim 5 wherein said cam members respectively comprise a bushing attached to the said bracket frame and positioned around the aperture thereof, and a collet rotatable on said shaft, said collet being provided with a knurled radial flange means for rotating the same, one of said cam members having at least one female dovetail or V-shaped slot adjacent the other cam member, the second cam member having at least one matching V-shaped male dovetail portion adapted to be received within the female dovetail portion and alternatively upraisable by means of said radial flange for positioning said dovetail portions out of registry, with the male dovetail portion resting upon the upper edge of the opposite cam member.

7. The device according to claim 6 further including a cap nut and a jam nut secured against one another on an upper threaded portion of said shaft on the remote side of said cam members from said bracket frame.

8. The device according to claim 4 wherein said bracket frame comprises an angular steel member having a lower portion thereof which is adapted to be secured to the main frame, and carrying said arcuate shoe by an upper portion thereof angularly related to the lower portion.

9. The device according to claim 4 further including an apron extending from said bracket frame in substantially parallel relation to the said shaft as well as in substantially perpendicular relation to said bracket frame, said apron extending to a position adjacent said arcuate shoe.

10. The device according to claim 9 wherein said apron has an arcuate edge adjacent said arcuate shoe, said arcuate edge having a forward contour substantially matching that of the arcuate shoe.
